UNITED STATES PATENT OFFICE.

JOHN TAMBERLIN, OF PHILADELPHIA, PENNSYLVANIA, ASSIGNOR TO THE GEORGE W. BLABON COMPANY, OF PHILADELPHIA, PENNSYLVANIA, A CORPORATION OF PENNSYLVANIA.

SHEET-LINOLEUM DISINTEGRATOR.

Application filed November 2, 1920. Serial No. 421,278.

This invention is a machine designed primarily for disintegrating sheets of linoleum from which shapes have been punched for making inlaid linoleum, but it will be understood that it is not limited to operation upon sheets of this character.

The invention is characterized by a revolute member (as a cylinder) provided with projecting devices (as rearwardly bent fingers) spaced along the axis of revolution; a set of downwardly projecting stationary devices (as fingers inclined at a small angle to the vertical) spaced along said axis of revolution so as to be passed in alternating relation by the devices first named; a chute extending downwardly from the punching machine for carrying the sheets to be disintegrated over the devices second named where they are engaged in shearing relation 20 by the revolving devices first named; stationary projecting devices or strippers spaced along said axis of revolution in alternating relation to the devices first named and adapted for disengaging the broken or 25 disintegrated material therefrom and from the cylinder, and means comprising a conveyor for carrying away the broken material.

This mechanism, in the preferred practice, is combined with mechanism through which sheets are fed and by which shapes are punched therefrom, as in the manufacture of inlaid linoleum, the shapes being removed from the sheets and the remainder 35 being fed down the chute to the disintegrating mechanism.

The invention is embodied in the mechanism set out in the following description and the accompanying drawings in illustration thereof.

In the drawings, Fig. 1 is a sectional elevation of mechanism for feeding and punching linoleum sheets in combination with my improved means for disintegrating and 45 moving the punched sheets; Fig. 2 is a part sectional plan view taken on the line 2^x—2^x of Fig. 1, and Fig. 3 is an irregular sectional view taken on the line 3^x—3^x of Fig. 1.

In the machine illustrated, the linoleum sheet 1 is moved intermittently, over a perforated stripper plate 2 and beneath a template 3, between the block 4 having the dies 5 thereon and the head 6. The movements 50 of the sheet are effected by known carrier

mechanism comprising the endless belts 7 which pass over the wheels 8, 9 and 10, the latter being driven by a sprocket wheel 11 fixed thereto; a sprocket chain 12 passing thereover, a sprocket wheel 13 over which the chain passes, a pinion 14 fixed to the wheel 13 and a spur wheel 15 which drives the wheel 14 and the carriage 15' having grippers 15^a and 15^b for engaging the sheet.

The block 4 is elevated by the rotary cams 16 which are connected to operate together by the meshing spur wheels 17 and act on rollers 18 on the block. The plate 2 is caused, by the elevation of the block, to press the sheet 1 against the template 3, and the template (carried by the bolts 19 movable in the frame 15') is carried thereby against the frame. The dies 5 punch the desired shapes 1' from the sheet by passing therethrough, forcing the shapes into the corresponding apertures in the template. Thereupon the block 4 falls by gravity as the cams 16 are revolved further, the plate 2 stripping the perforated sheet from the dies 5 as they are withdrawn.

The punched section of the sheet 1 is fed down the steeply inclined chute 20 into a box 21 through its top aperture 21'.

A bar 22, which is disposed across the aperture at the bottom of the chute, is provided with the spaced downwardly extending projections or fingers 23 inclined at a small angle to the vertical and over which the punched sheet passes.

A cylinder 24, journalled in the box 21, is provided with the projections or fingers 25 spaced along its axis so as to pass between the fingers 23 in alternating relation thereto. The fingers carried by the cylinder are disposed or bent rearwardly with relation to the direction of their revolution so that the sheet engaging parts thereof shall be substantially parallel to the fingers 23 in passing them and shall act therewith in shearing relation, instead of pulling and tearing the sheet; the ends of the revolving 95 fingers acting in shearing relation to the bar 22 as well as to the fingers 23.

A bar 26, supported in the box 21, has fingers or strippers 27 fixed thereto in spaced relation so that the fingers 25 shall pass between them in alternating relation, the strippers detaching broken linoleum adhering to the cylinder 24 and the fingers 25.

The disintegrated linoleum, which falls from the cylinder 24 and the fingers 25, passes between the frame members 28 and falls upon the chute 29, which delivers it, 5 within the box, to the travelling belt or conveyer 30, the latter running through the aperture 21" in the side of the box.

The cylinder 24 and the belt 30 are operated in unison from the journalled shaft 31 having thereon the spur wheel 32 and the sprocket wheel 33. The wheel 32 drives a pinion 34 fixed to the cylinder 24. The sprocket wheel 33 drives a chain 35 which passes over a sprocket wheel 36, the latter being fixed to a journalled shaft 37 having fixed thereon a pulley 38 over which passes the belt 30.

Having described my invention, I claim:

1. In a machine of the character described, 20 the combination of a sheet conveyor, a slotted member to which a sheet is delivered by said conveyor, and a distintegrator comprising a revoluble member having fingers movable through the slots in said slotted member, said fingers being so shaped as to

engage a sheet on the slotted member substantially at right angles to the surface thereof, said slotted member and revoluble member cooperating to shear the sheet without substantial pull thereon longitudinally.

2. In a machine of the character described, the combination of a chute having a bar adjacent the mouth thereof with spaced downwardly projecting fingers thereon, a revoluble member having fingers thereon movable between the fingers first named, said revoluble fingers being bent rearwardly with relation to the direction of their revolution and having their sheet 35 engaging parts substantially parallel to the fingers first named in passing them, a stripper having fingers through which said revoluble fingers pass, and a conveyor to which material disintegrated by said fingers is discharged.

Signed at Philadelphia, in the county of Philadelphia and State of Pennsylvania, this 22nd day of October, 1920.

JOHN TAMBERLIN.
